UNITED STATES PATENT OFFICE

2,546,622

DETACHABLE SPUR FOR ROLLER SKATES

Jack Abel, Flushing, N. Y., assignor to D. P. Harris
Hdw. & Mfg. Co., Inc., New York, N. Y., a cor-
poration

Application January 23, 1950, Serial No. 139,973

1 Claim. (Cl. 280—11.37)

1

This invention relates to roller skates in general, and to play skates for youngsters in particular.

It is an object of the present invention to provide for the detachable mounting of simulated spurs on conventional roller skates so as to enable youngsters to style their roller skates for the occasion of playing outdoor games involving horseback riding, such as playing cowboy, for instance.

It is another object of the present invention to provide for detachability of the simulated spurs from conventional roller skates so that the spurs may be removed and the roller skates used in their conventional form.

It is another object of the present invention to render roller skates generally more attractive to youngsters, by providing roller skates with a spectacular display of spurs and thereby associate roller skating with horseback riding in the minds of youngsters and suggest to them new kinds of entertaining activity with their skates.

The above and other objects, features and advantages of the present invention will be more fully understood from the following description considered in connection with the accompanying illustrative drawings.

In the drawings:

Fig. 1 is a fragmentary side elevation of a roller skate embodying the present invention;

Fig. 2 is a fragmentary top plan view of the same roller skate; and

Fig. 3 is a section taken on the line 3—3 of Fig. 2.

Referring to the drawings, and more particularly to Figs. 1 and 2 thereof, the reference numeral 10 designates a roller skate having the usual foot and heel plates 12 and 14, respectively, which are customarily telescoping to permit lengthening or shortening of the skate. The plates 12 and 14 may, in accordance with conventional practice, be locked in their lengthwise adjusted relative position by a screw 15 which is accessible from below. The plates 12 and 14 are provided with conventional supports 18 and 20 for front and rear pairs of rotary rollers 22 and 24, respectively. The foot plate 12 of the skate may, for its attachment to the sole of the wearer's shoe, be provided with the usual adjustable clamping jaws (not shown). The heel rest 16, which is customarily provided on the heel plate 14, may be apertured on opposite sides, as at 30, for the passage therethrough of a leather or other strap 32 having a conventional buckle 34 for releasably closing the strap on the wearer's

ankle and thereby securing the heel rest 16 and heel plate 14 of the skate to the wearer's foot. The heel rest 16, which is customarily curved in approximation of the wearer's heel (Fig. 2), usually extends only around the end of the heel plate 14, and the remaining opposite margins 34 and 36 of the latter plate are preferably left exposed on the skate for a purpose hereinafter described. The roller skate described herein may in all respects be conventional.

The roller skate 10 is, in accordance with the present invention, provided with the spectacular display of a simulated horseback rider's spur 40, which comprises a mounting fork 42 and a spur point 44. The spur point 44 is, in the present instance, a star-like wheel of the kind usually employed in rowel spurs, and may conveniently be rotatably mounted at 46 in rearward extensions 48 and 50 of the prongs 52 and 54, respectively, of the spur fork 42. The prongs 52 and 54 of the spur fork 42, which may conveniently be joined by a rivet 56, are preferably made of spring steel or a similar resilient material so that they may engage the heel rest 16 of the skate with a yielding force when straddling the same in the mounted fashion shown in Figs. 1 and 2.

For detachably mounting the spur 40 on the roller skate, the opposite ends 60 and 62 of the prongs 52 and 54, respectively, of the spur fork 42 are, in the present instance, formed into channel shape (Fig. 3) so as to be snappable over the adjacent margins 34 and 36, respectively, of the heel plate 14 of the skate. Thus, in order to apply the spur 40 to the skate 10, it is merely necessary to force the spur fork 42 over the heel rest 16 until the channel-shaped ends 60 and 62 of the former are in position to be snapped over the adjacent margins 34 and 36, respectively, of the heel plate 14. Removal of the spur 40 from the roller skate is even simpler, requiring mere forceful retraction of the spur rearwardly away from the skate, as will be readily understood.

While the instant spur 40 is detachably mountable on the roller skate, it is fully within the purview of the present invention to provide the spur on the skate as a permanent part thereof. Thus, regardless of whether the spur 40 is a permanent part of the roller skate or is detachably mounted thereon, the display of the spur on the roller skate is spectacular to most youngsters and, by associating in their minds roller-skating with horseback riding, suggests to them new kinds of entertaining activity with their skates. Thus, the display of spurs on roller skates does

suggest to most youngsters to enlarge upon mere roller-skating by playing such popular games as cowboy, for instance, while on skates. Aside from inducing youngsters to enter into outdoor games which add their thrills to those of roller-skating, the display of spurs on roller skates satisfies to a considerable extent a youngster's natural desire to bear some resemblance to the character which he or she portrays in playing. The detachability of the spur 40 has, of course, the advantage of enabling youngsters to mount the spurs for playing games involving horseback riding, and to leave them off on other occasions.

While I have shown and described the preferred embodiment of my invention, it will be understood that various changes may be made in the present invention without departing from the underlying idea or principles of the invention within the scope of the appended claim.

Having thus described my invention, what I claim and desire to secure by letters patent, is:

A detachably mountable simulated horseback rider's spur for a roller skate having a heel-supporting plate and an upwardly projecting heel

rest, said spur comprising a resiliently spreadable mounting fork with opposite channel-shaped ends and a rearwardly projecting spur point substantially centrally of said fork, said channel-shaped fork ends being adapted to be snapped over opposite margins, respectively, of the heel plate of a skate for detachably mounting said spur on the latter in position thereon in which said fork straddles the heel rest and said point extends rearwardly from the latter to simulate normal wear of said spur on the heel of the wearer of the skate.
